UNITED STATES PATENT OFFICE

116,321

DESIGN FOR A TRAILER

Walker L. C. Huxter, Richmond, Va.

Application June 24, 1938, Serial No. 78,036

Term of patent 14 years

To all whom it may concern:

Be it known that I, Walker L. C. Huxter, a citizen of the United States, residing at Richmond, in the county of Henrico and State of Virginia, have invented a new, original, and ornamental Design for a Trailer, of which the following is a specification, reference being had to the accompanying drawing, forming a part thereof.

Fig. 1 is a perspective view of a trailer showing my new design; and

Fig. 2 is a front view of the same trailer.

The dominant features of my design reside in the portions shown in full lines. The two sides of my trailer are generally similar, configuratively, and Fig. 1 is illustrative of features of design characterizing either side.

I claim:

The ornamental design for a trailer, as shown and described.

WALKER L. C. HUXTER.
